CLAIM

The ornamental design for a mandoline, as shown and described.

DESCRIPTION

FIG. 1 is a top perspective view of a mandoline showing our new design;

FIG. 2 is a bottom plan view thereof;

FIG. 3 is a top plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken lines shown in the figures depict a cutting blade and rectangular shapes of the mandoline that form no part of the claimed design.
